GRAPE SHEAR HANDLE

Alexander E. Lewis, Brooklyn, N. Y.

Application May 21, 1954, Serial No. 30,602

Term of patent 3½ years

(Cl. D22—5)

FIG. 1.

The side opposite to that shown in Figure 1 presents a substantially similar appearance as the top plan shown in said figure.

I claim:

The ornamental design for a grape shear handle, substantially as shown and described.
